UNITED STATES PATENT OFFICE.

FREMONT BARTLETT CHESBROUGH, OF BOSTON, MASSACHUSETTS.

CUP.

1,208,483.

Specification of Letters Patent. Patented Dec. 12, 1916.

Application filed June 22, 1916. Serial No. 106,355.

To all whom it may concern:

Be it known that I, FREMONT B. CHESBROUGH, a citizen of the United States, and a resident of Boston, in the county of Suffolk and State of Massachusetts, have invented a new and improved Cup, of which the following is a full, clear, and exact description.

The object of my invention is to provide an inexpensive cup which may be used for selling hot coffee and other liquids on trains and in other places, the cup being so constructed that it will keep the coffee or other liquid hot for a considerable period of time.

Additional objects of the invention will appear in the following specification in which the preferred form of the invention is described.

In the drawings similar reference characters denote similar parts in all the views, in which—

Figure 1 is a sectional view on the line 1—1 of Fig. 2; Fig. 2 is a sectional view of the cup taken on the line 2—2 of Fig. 1; and Fig. 3 is a fragmentary plan view of the cup with the cover removed.

By referring to the drawings, it will be seen that the cup is constructed with an outer stiff paper member 5 forming a side wall 6, and a bottom 7, there being an impervious paper member 7 disposed within the outer stiff paper member 5, this impervious paper member 7 having sides 8 and a bottom 9. I prefer to make use of paraffined waterproof paper for this inner impervious member 7. The stiff outer paper member 5 and the impervious paper member 7 are spaced from each other, and are held in position relatively to each other by corrugated members, a corrugated member 10 being disposed between the bottom 7 of the outer stiff paper member 5 and the bottom 9 of the impervious paper member 7, and a corrugated paper member 11 being disposed between the side wall 6 of the stiff paper member 5 and the side wall 8 of the impervious paper member 7. The upper edges of the stiff paper member 5 and the impervious paper member 7 and the corrugated paper member 11 are rolled together as shown at 12, this means being provided for holding the several members in position.

Extending inwardly from the side wall 8 of the impervious paper member 7, there are projections 13 which may be disposed in bayonet slots 14 in a stiff paper member 15

which forms a part of the cover for the cup. This stiff paper member 15 engages the upper portions of the side wall 8 of the impervious paper member 7 the inner surface of 60 the stiff paper member 15, being connected by an impervious paper member 16 over which is disposed two stiff paper members 17 which engage each other and which also engage the impervious paper member 16 at 65 a central point 18. The edges of the two stiff paper members 17, together with the upper edge of the stiff paper member 15, are rolled together as shown at 19, as a means for holding the parts of the cover in 70 position relatively to each other.

It will be seen that by the construction which has been described, an inexpensive cup is provided in which liquids such as coffee may be sold, the air spaces formed by the 75 corrugated members 10 and 11 and the air spaces between the impervious paper member 16 and the stiff paper member 7, serving to keep the coffee or other liquid hot for a considerable period.

The cover for the cup is normally held in position on the cup by means of the engagement of the projections 13 extending inwardly from the impervious paper member 7 of the cup, with the bayonet slots 14 85 formed in the stiff paper member 15 of the cup cover.

Having thus described my invention, I claim as new, and desire to secure by Letters Patent:

1. In a cup, an outer wall, an inner wall spaced therefrom, and corrugated material separating the inner and outer walls, the upper ends of the two walls and of the corrugated material being rolled together, for 95 the purpose specified.

2. In a cup, an outer wall of stiff paper, an inner wall of impervious paper spaced therefrom, and a corrugated stiff paper member connecting the two walls, the upper 100 ends of the stiff paper member, the impervious paper member and the corrugated paper member being rolled together, for the purpose specified.

3. In a cup, an outer wall of stiff paper, an inner wall of impervious paper spaced therefrom, a corrugated stiff paper member connecting the two walls, the upper ends of the stiff paper member, the impervious paper member and the corrugated paper 110 member being rolled together, a cover for the cup consisting of a stiff paper member for

- 2
- engaging the inner portions of the cup, an impervious paper member connecting the inner portions of the stiff paper member of the cover, and an additional stiff paper member spaced above the body of the last mentioned impervious paper member, the last two mentioned stiff paper members having their edges rolled together for the purpose specified.
- 10 4. In a device of the class described, a cover consisting of a stiff paper member for engaging the inner portions of a cup, an impervious paper member connecting the inner portions of the stiff paper member, and a second stiff paper member spaced above the body of the impervious paper member, the two stiff paper members having their edges rolled together for the purpose specified.
5. In a cup, an outer wall of stiff paper, an inner wall of impervious paper spaced 20 therefrom, a corrugated stiff paper member connecting the two walls, the upper ends of the stiff paper member, the impervious paper member and the corrugated paper member being rolled together, a cover for 25 the cup consisting of a stiff paper member for engaging the inner portions of the cup, an impervious paper member connecting the inner portions of the stiff paper member, an additional stiff paper member spaced above 30 the body of the last mentioned impervious paper member, the last two mentioned stiff paper members having their edges rolled together, and a bayonet joint lock for holding the cover in place on the cup.

FREMONT BARTLETT CHESBROUGH.
